UNITED STATES PATENT OFFICE.

CYRIL A. BRIGHAM, OF EAST ORANGE, NEW JERSEY, ASSIGNOR TO BRANDES LABORATORIES, INC., OF NEWARK, NEW JERSEY, A CORPORATION OF NEW JERSEY.

ELECTROMAGNETIC SOUND REPRODUCER.

Application filed September 13, 1926. Serial No. 135,192.

My invention relates broadly to electromagnetic sound reproducers and more particularly to a construction of power type loud speaker reproducer for the accurate 5 reproduction of articulate speech and music.

One of the objects of my invention is to provide a loud speaker reproducer having parts arranged for the reproduction of 10 sound at large amplitude with substantial- 50 ly no distortion.

Another object of my invention is to provide a loud speaker reproducer which does not employ a magnetic armature member as 15 the movable element of the loud speaker, but which in lieu thereof is provided with a flat coil structure of extremely small mass, which is connected in the output circuit of 20 an amplifier system and which is longitudinally movable within an intense magnetic field.

A still further object of my invention is to provide a substantially distortionless sound reproducer having means for changing 25 the reactance of the reproducing circuit in proportion to variations in frequency of the incoming signaling energy for the faithful reproduction of sound.

A still further object of my invention resides in the arrangement of a flat coil within 30 an intense magnetic field with conductive plate members positioned on opposite sides of the movable coil member for changing the reactance of the movable coil in 35 proportion to the variation in frequency of the incoming signaling energy for maintaining the operating characteristic of the sound reproducer in a substantially uniform condition.

Still another object of my invention is to provide a loud speaker reproducer having 40 a movable member vibratile in accordance with electrical vibrations which movable member has a natural period far removed 45 from the normal voice or music frequencies.

Still another object of my invention is to provide a construction of sound reproducer employing a flat longitudinal movable member which connects with a sound re-

producing diaphragm for imparting vibrations thereto for the reproduction of sound at large amplitude.

My invention will be more clearly understood by reference to the accompanying drawings wherein:

Figure 1 is a rear view of the assembled power speaker of my invention; Fig. 2 is a top plan view of the power speaker; Fig. 3 is a side elevation of the power speaker with parts of the sound reproducing dia- 60 phragm and support therefor broken away and illustrated in cross-section; Fig. 4 is a cross-sectional view through the power speaker taken on line 4—4 of Fig. 2 and showing the flat longitudinal movable coil 65 member employed in the power speaker; Fig. 5 is a perspective view of one of the conductive plate members which I provide in association with the pole pieces of the power speaker; Fig. 6 is a fragmentary 70 cross-sectional view taken through the electromagnetic operating structure of the power speaker; Fig. 7 is a side view of the insulated structure on which the driving coils are supported; Fig. 8 is a plan view 75 of the driving coil assembled upon the insulated structure of Fig. 7; Fig. 9 is a cross-sectional view through the driving member taken on line 9—9 of Fig. 8; Fig. 10 is an enlarged cross-sectional view 80 through the driving coils taken on line 10—10 of Fig. 8; Figs. 11 and 12 are front and sectional views of one of the spiders for suspending the driving coils for movement 85 between the pole pieces of the electromagnetic system; and Figs. 13 and 14 show front and sectional views of the end members upon which the spiders are mounted 90 for centering the driving coils between the pole pieces.

Heretofore in the art it has been customary to employ a type of electromagnetic driving mechanism for sound reproducers where a diaphragm or armature has generally been employed as the vibrating element. The method of mounting or clamping the armature or diaphragm for operation in the sound reproducer and the physical dimensions 95

- thereof have introduced very marked limitations in the operating characteristics of such electromagnetic reproducers. The physical structures have inherently introduced strong 5 mechanical resonances which are detrimental to the correct response of the reproducer over the complete frequency range encountered in radio broadcast reception thereby impairing the quality of the reproduction.
- 10 Realizing the serious limitation offered by mechanical resonances of the armature or diaphragm in an electromagnetic sound reproducer, I have devised an electromagnetic sound reproducing system having a vibratory element therein operating substantially 15 independently of mechanical resonances. I provide an electromagnetic field of relatively large strength and in this field suspend a flat movable coil member of extremely light 20 weight. The signaling energy is introduced into the movable coil member which is mechanically vibrated for imparting movement to a sound reproducing diaphragm. I provide a novel method of suspending the movable 25 coil member whereby longitudinal movement of the coil member between the pole pieces of the electromagnetic system may be effected without change in the spacial relation between the sides of the movable coil 30 and the pole pieces. In order to improve the operating characteristics of the power speaker I provide conductive shields adjacent the pole pieces and the movable coil, in which shields eddy currents are introduced for 35 changing the reactance of the coil system at higher frequencies for insuring a more uniform reproduction of musical notes over the entire frequency range.
- Referring to the drawings in more detail 40 I have represented the power speaker as suspended from the top 1 of a cabinet structure by means of bolt members 2 to which brackets 3 are secured. The power speaker consists of a frame structure made up of 45 plate members 4 and 5 clamped at opposite ends by means of bolt members 9 and 10 on opposite sides of the laminated magnetic core structure 11 with spacer members 6 between the surfaces of panels 4 and 5 and the 50 core structure. The plate members 4 and 5 are cut away at their central portions as represented at 4^a and 5^a and the supporting plates 7 secured thereto from which the spider members 8 are suspended.
- 55 The spider members 8 are shaped as represented more clearly in Figs. 1 and 11 having a pair of side suspension arms 8^c and 8^d and a pair of central arms 8^a and 8^b extending in opposite directions along the axis thereof for supporting the flat form 12 in a plane which passes through the power speaker between the pole tips 14 and 15 which extend from the laminated core members 11 on which the electromagnetic windings 16 and 17 are carried. The pole pieces 14 and 15 are clamped by means of strip members 18 and 19 by bolt members 18^a and 19^a forming a rigid structure. The pole pieces are encased in conductive cap members 20 and 21, each of the cap members 70 having cut away portions 20^a and 20^b and 21^a and 21^b into which the pole pieces fit.
- In Fig. 5 I have illustrated in perspective view one of the caps 20 having pockets 20^a and 20^b therein to receive the pole pieces 75 and present a flat conductive surface closely parallel to the coil form 12.
- The coil form 12 is constructed of extremely light weight insulating material and is substantially in the form of a skeleton 80 upon which coils 22 and 23 are supported on opposite sides thereof. These coils are wound substantially flat and secured to opposite sides of the coil form 12. The coils are relatively narrow in width, seldom being 85 more than one-half inch wide. Aluminum wire is chosen for securing the lightest possible weight in the driving system. The coils 22 and 23 are secured to the flat surfaces of the coil form 12 and are secured to each 90 other, as represented at 24, beyond the limits of the coil form 12. The coil form 12 is provided with projecting studs 12^a, 12^b, 12^c and 12^d by which the coil form is supported between the spider 8 and by which 95 the driving forces may be delivered from the longitudinally vibratile coil to the sound reproducing diaphragm.
- By reason of the flat construction of the driving coil the spacial relation or gap 100 between the sides of the coils 22 and 23 and the conductive plate members 20 and 21 may be maintained extremely small.
- I provide connecting members of aluminum represented in Fig. 4 at 25^a, 25^b, 25^c, 105 and 25^d which are secured over the studs 12^a, 12^b, 12^c and 12^d of the coil support 12 for aligning the coil support with the ends of the spider arms 8^a and 8^b and suspending the coils for lateral movement with respect 110 to the pole pieces 14 and 15. An aluminum connecting member 25^d is secured to the stud 12^d to which a rod member 26 is connected passing through the aperture 8^c in the spider 8 and connecting to the apex piece 27 of 115 the sound reproducing diaphragm 28. The sound reproducing diaphragm 28 is illustrated as consisting of an elliptically shaped fibrous surface substantially free to vibrate at its peripheral edge by virtue of the flexible 120 suspension 29 by which the peripheral edge 30 of the diaphragm is suspended within the elliptical aperture 31 of the plate 32. The plate 32 is supported from the frame of the power speaker by means of brackets 33 125 forming a rugged structure.
- The construction of the spider members 8 is the result of extended research and development for securing strictly lateral movement of the vibratory coils 22 and 23 130

without side wiping with respect to the pole pieces or the conductive plate members 20 and 21.

The field windings 16 and 17 are excited 5 from a suitable source of direct current and the signaling current from the output of the loud speaker electron tube amplifier, connected with the signal receiving apparatus supplied to the coils 22 and 23. The connection of the coils 22 and 23 with the output 10 circuit of the power amplifier is such that the signaling current passes through the two coils in parallel. The electromagnets comprising the field windings are connected in 15 series in such manner that opposite poles are directed toward each other for creating a flux which cuts the turns of the windings on the movable coil support whereby a driving torque is developed which tends to move 20 the vibratory coil at right angles with respect to the concentrated field between the pole pieces 14 and 15. The position of the plates 20 and 21 serves to change the reactance of the driving coils at the higher 25 frequencies rendering the operating characteristics of the loud speaker system more uniform over the entire range of musical notes.

The embodiment of my invention illustrated in the drawings has been found to be 30 very practical in construction and capable of manufacture and production on a quantity basis with uniform characteristics in the many loud speakers passing through a production program.

The operation of the power speaker is 35 such that the reproduction is extremely faithful with respect to the modulation at the broadcasting station inasmuch as the mechanical resonances in the reproducing 40 system have been eliminated.

While I have described my invention in 45 certain preferred embodiments, I desire that it be understood that modifications may be 50 made and that no limitations upon the invention are intended other than are imposed by the scope of the appended claims.

What I claim as new and desire to secure 55 by Letters Patent of the United States is as follows:

1. In an electromagnetic sound reproducing apparatus an electromagnetic field system including a plurality of pole pieces directed toward each other and separated by 55 a gap, a pair of conductive members positioned over said pole pieces forming substantially parallel walls, a flat coil member resiliently suspended between said parallel walls, a sound reproducing diaphragm mechanically connected with said flat coil member, said coil member being energized by 60 variable signal currents for the setting up of mechanical vibrations in a direction substantially normal to the direction of said 65 pole pieces whereby corresponding vibra-

tions are imparted to said sound reproducing diaphragm.

2. In an electromagnetic sound reproducer, an electromagnetic operating system including a plurality of pole pieces directed toward each other and separated by a narrow gap, a flat insulated coil support flexibly suspended in said gap, a flat coil member disposed on each side of said flat coil support, a sound reproducing diaphragm, a connection between said sound reproducing diaphragm and said flat coil support, said coil members being energized by variable signaling current whereby said coil support is subjected to mechanical vibrations in a direction substantially normal to the direction of said pole pieces for imparting corresponding vibrations to sound reproducing diaphragm, 70 75 80

3. In an electromagnetic sound reproducing system an electromagnetic field including a plurality of pole pieces directed toward each other and separated by a gap, a sound reproducing diaphragm and a flat coil structure disposed in said gap and mechanically connected with said sound reproducing diaphragm, means for flexibly mounting said flat coil structure at opposite ends thereof for lateral movement in said gap in a line substantially normal to said pole pieces, said coil structure being energized by variable signaling current and arranged to vibrate substantially independent of mechanical resonances for imparting corresponding vibrations to said sound reproducing diaphragm, 85 90 95 100

4. In an electromagnetic sound reproducer an electromagnetic field system including a plurality of pole pieces directed toward each other and separated by a narrow gap therebetween, a flat coil support, means at each side of said electromagnetic field system for flexibly suspending said flat coil system said means comprising flat sheets of relatively thin flexible material rigidly connected with said flat coil support for permitting movement of said coil support in said narrow gap substantially normal to the direction of said pole pieces, a sound reproducing diaphragm connected with said flat coil support and a flat coil member carried by said flat coil support and arranged to be energized by variable signaling current whereby vibrations may be imparted to said sound reproducing diaphragm substantially free of mechanical resonances, 105 110 115 120

5. In an electromagnetic sound reproducer, a frame structure, an electromagnetic operating mechanism carried by said frame structure including pole pieces directed toward each other and separated by a relatively narrow gap, a flat coil support disposed in said narrow gap, means carried by said frame structure at opposite ends of said gap for flexibly suspending said flat coil support for 125 130

- movement in a plane substantially normal to the direction of said pole pieces, a sound reproducing diaphragm flexibly suspended from said frame structure, a connection between said diaphragm and said flat coil support and a winding carried by said flat coil support and arranged to be energized by variable signalling current whereby vibratory motion may be imparted to said flat coil support for transferring corresponding vibrations to said sound reproducing diaphragm.
6. In an electromagnetic sound reproducing system a frame structure, an electromagnetic operating mechanism carried by said frame structure having its pole pieces directed toward each other and separated by a relatively narrow gap, spider members located on each side of said frame structure at opposite ends of said gap, a flat coil support carried between said spider members, a sound reproducing diaphragm flexibly suspended from said frame structure and connected at its apex with said flat coil support, a winding carried by said flat coil support and arranged to be energized by variable signal currents whereby vibratory movement in said gap is effected for imparting corresponding movement to said sound reproducing diaphragm.
7. In an electromagnetic sound reproducing system, a frame structure, an electromagnetic operating mechanism carried by said frame structure having its pole pieces directed toward each other and separated by a relatively narrow gap, means carried by
- 40 said frame structure at opposite ends of said gap for flexibly suspending a flat coil structure in said gap, a pair of conductive liners for said gap on opposite sides of said coil structure, a sound reproducing diaphragm flexibly suspended from said frame structure and connected with said flat coil structure and a winding carried by said flat coil structure and arranged to be excited by variable signaling current whereby vibration 45 developed in said flat coil structure may be imparted to said sound reproducing diaphragm.
8. An electromagnetic sound reproducer comprising a frame structure, an electromagnetic field system including a plurality of pole pieces directed toward each other and separated by a narrow gap therebetween, a flat coil support, spider members located at opposite ends of said narrow gap, said spider members having a pair of arms secured to said frame structure and another pair of arms secured to said flat coil support for guiding said coil support laterally between said pole pieces, a sound reproducing diaphragm, a connection between said flat coil support and said diaphragm and a winding carried by said flat coil support and arranged to be energized by variable signaling current, whereby vibrations imparted to said flat coil support are transmitted to said sound reproducing diaphragm.

In testimony whereof I affix my signature.

CYRIL A. BRIGHAM.
